By his Attorney
George C. Heinrichs

UNITED STATES PATENT OFFICE

GOTTHILF LEHMANN, OF BRONX, NEW YORK.

COMBINATION ELECTRIC LIGHT AND PERFUME DISPENSER

Application filed June 13, 1929. Serial No. 370,690.

This invention relates to improvements in perfume vaporizers, particularly to an electrically operated vaporizer having the form of an incandescent electric lamp, and adapted to simultaneously serve as perfume diffuser and light.

It is the principal object of my invention to provide a vaporizer of this character adapted to be associated with electric fixtures and one which is attractive and ornamental in appearance, color and shape, yet comparatively simple and inexpensive, while efficient in disseminating and diffusing a perfume and which may simultaneously serve as light.

Another object of my invention is the provision of a vaporizer and lamp equipped with the customary vacuum chamber containing the filaments, one of which is formed as an electric resistance wire in order to develop the heat required for thoroughly diffusing a particular perfume contained in a wad of asbestos wool or other suitable material saturated with the particular perfume.

The lamp is so constructed as to allow the pouring of a few drops of liquid perfume into the same for evaporation and diffusion.

The other of the filaments may be any type of customary light filament, and such light filament may also be used alone for developing the heat required for diffusing a perfume.

A further object of my invention is the provision of a combination perfume diffuser and electric lamp or light particularly well adapted for use on Christmas trees, as it is ornamental and pleasing to the eye of an observer in shape, size and color. In this instance preferably a wad of asbestos wool or the like saturated with a pine essence or extract is used to simulate, if for instance used with artificial Christmas trees, the pine odor incident to the live pine or fir trees.

A still further object of my invention is the provision of a perfume vaporizer of simple construction in form of an electric light bulb which may readily be attached to any light socket of a fixture within the light circuit of a house to diffuse a perfume or deodorant for purifying the air in a room, while simultaneously on account of its decorative features it is adapted to serve as an ornament

for any room, harmonizing in color and shape with the decoration of a room and the furniture contained therein.

These and other objects and advantages of my invention will become more fully apparent as the description thereof proceeds and will then be specifically defined in the appended claims.

In the accompanying drawing forming a material part of this disclosure:

Fig. 1 is a sectional view illustrating the internal construction of a perfume vaporizer in form of an electric lamp constructed according to my invention.

Fig. 2 is a side elevation of another embodiment of the invention, parts being broken away to better illustrate the interior construction.

Fig. 3 illustrates in front elevation a closure device.

Fig. 4 is a side view thereof.

Fig. 5 is a sectional elevation of a further modification of my invention, suitable for use on Christmas trees or the like.

Fig. 6 is a front elevation thereof.

As illustrated in Figure 1, the novel and improved perfume vaporizer has the form of an electric light bulb or lamp 10 of conventional shape, seated in the usual screw socket 11.

A vacuum chamber 12 is provided within bulb or shell 10, and the customary loop-shaped glass filament holder 13 therein contains a coil 14 of heat resisting wire, the ends of which are connected in the usual manner to the socket and its contact.

The chamber 15 surrounding the chamber 12 is adapted for the reception of asbestos wool or any like suitable material saturated with a perfume, for instance pine extract to be diffused or disseminated.

The lower, open end of bulb 10 is equipped with a suitable socket 16 extending into its interior, and adapted to be closed by any suitable means, as a cork, or the like, or as shown by a plate or disc 17 on which two suitably bent spring fingers 18, 19 are mounted allowing upon their compression a ready introduction into the socket 16 and holding the closing disc in place. A hook 20 on the

90

95

100

outer face of disc 17 is adapted for the attachment of one end of a chain 21, the other end of which is attached to an eye on the outer face of socket 16. In the embodiment 5 of my invention illustrated in Figure 2, the outer face of bulb 22 seated in socket 23, has an attractive and ornamental appearance resembling for instance a pine-apple or the like, as indicated by reference numeral 24.

10 Into the vacuum chamber 25 formed within bulb 22 extends a loop-shaped filament holder 26 containing in this form a filament wire 27, as it is customarily used in incandescent lights. The lower open end of the 15 bulb 22 is also closed by a disc 17, shaped and constructed as described above with respect to the form of my invention illustrated in Figure 1.

Also here the chamber surrounding chamber 25 is adapted to receive a wad of asbestos wool or similar material treated with an odorous material.

10 In the form of my invention illustrated in Figures 5 and 6 the bulb 28 seated in socket 5 29 is comparatively small and particularly well adapted for use on Christmas trees or the like.

Its outer mantle may be any color and shape and shows any desired decorative or 30 ornamental design.

In its interior the bulb 28 contains a filament holder 30 within chamber 31, and holding a light filament 32 of conventional type.

The lower, open end of the bulb in this 35 form is closed by a gelatinous cover 33, or the like.

The chamber 31 is adapted to receive a wad of asbestos wool 34 or similar suitable material adapted to be saturated with a perfume or fragrant extract or essence.

40 The operation of my device will be entirely clear from the above description and simultaneous inspection of the drawing, and it will be evident that upon connecting the 45 lamps to the light circuit of a house the heat developed by the resistance wire or the light filament will volatilize the odor or perfume in the wool and the same will spread in a room, and perfume the same. In case the 50 smaller lights illustrated in Figures 5 and 6 are used on Christmas trees, particularly artificial Christmas trees, the evaporating perfume preferably pine extract will simulate the odor of a real pine tree.

55 It will be clear that if light filaments are used, the lamps or shells may be used not only for perfuming but also for illuminating purposes, and a few drops of a liquid perfume may readily be introduced into the lamp for 60 evaporation and diffusion.

65 It will be understood, that I have shown and described the preferred forms of my device only as examples of the many possible ways to construct the same in practice, and 70 that I may make such changes in their gen-

eral arrangement and appearance and in the construction of the minor details thereof as come within the scope of the appended claims without deviation from the spirit of my invention and the principles involved.

Having thus described my invention, what I claim as new, and desire to secure by Letters Patent is:

1. A vaporizer for use in rooms comprising a shell for the substance to be vaporized, said shell having an opening and comprising an outer glass mantle having substantially the form of a pine-apple, adapted to be suitably ornamented, a solid substance diffusing a perfume, an electrically operated heating element in said shell to vaporize the substance in said shell, a means for closing the lower end of said shell, and a socket in which the upper end of said shell is seated adapted to be attached to the light circuit of the room.

2. A perfume evaporator comprising a transparent outer casing having an open lower end, a socket in which the upper end of said casing is seated adapted to be screwed into a light fixture forming part of the light circuit of a house, an element within said shell adapted to be heated by the light current, and a wad of perfumed material near said element for diffusing the perfume during the heating of said element, and closing means for the open lower end of said casing.

3. A Christmas tree ornament having the shape of an ornamental pine-apple and comprising a shell having an opening, a light bulb in said shell, a socket therefor, said shell and bulb forming a chamber, a solid body in said shell diffusing perfume under the influence of the heat developed by said light, a plate for closing the opening of said shell, and spring fingers combined with said plate for holding the same in its opening closing position allowing a ready removal.

Signed at New York, in the county of New York and State of New York, this 10th day of June, A. D. 1929.

GOTTHILF LEHMANN.
